(57) **CLAIM**

The ornamental design for a two-passenger pedaled vehicle, as shown and described.

DESCRIPTION

FIG. 1 is a left-front perspective view of a two-passenger pedaled vehicle showing my new design, with the pedals, cranks, and springs being drawn in broken lines and not being part of my design.

FIG. 2 is a left side elevation thereof.

FIG. 3 is a front elevation thereof.

FIG. 4 is a right side elevation thereof.

FIG. 5 is a rear elevation thereof; and,

FIG. 6 is a top plan thereof.

The under side of the vehicle does not form any part of the claimed design.
